EGG CARTON SETUP MACHINE
Arthur E. Randles, Jr., 3000 Middlefield Road,
Redwood City, Calif.
Filed Feb. 6, 1963, Ser. No. 256,667
1 Claim. (Cl. 93—37)

My invention relates to mechanisms for erecting cartons into useable form to receive eggs. The cartons are initially provided in the form of blanks. These are customarily fabricated of fiberboard or cardboard and are cut, scored, perforated and glued to provide a carton blank which, when erected, has individual compartments for the eggs and has a cover overlying the eggs. One form of carton is also distinguished by an inverted V-shaped reentrant portion running along and upstanding from the bottom. This is interlocked with a number of transverse partitions so as to provide a central supporting wall extending from the base to the cover for strength. A carton of this kind is shown in Patent No. 2,946,497 issued July 26, 1960. The carton blanks are furnished with a lower panel having a plain trailing portion and a number of apertures in the leading portion thereof. There is also an upper panel folded at the leading edge and overlying the leading portion only of the lower panel and having its trailing end glued to the subjacent lower panel.

It is an object of the invention to provide a machine for receiving carton blanks in their partially folded and glued condition and erecting the blanks into rectangular bodies for reception of eggs.

Another object of the invention is to provide a machine which will automatically feed blanks in succession and erect them into egg receiving condition and discharge them from the machine.

Another object of the invention is to provide a carton setup machine effective to erect a carton having a reentrant, inverted V-shaped portion running along the bottom thereof and interlocking with a number of transverse partitions.

Another object of the invention is to provide an egg carton setup machine that operates well with cartons as commercially supplied despite the fact that they vary somewhat in size from time to time either by design or at random due to variations in humidity and other factors which change the dimensions of the fiberboard or paper stock.

A still further object of the invention is to provide an egg carton setup machine which goes through the setup cycle automatically and in a repetitive fashion with little or no supervision.

Another object of the invention is to provide an egg carton setup machine effective to operate on the cartons generally from below so that the operation of the machine can be readily checked and inspected from an observation point above.

A still further object of the invention is to provide an egg carton erecting machine which is direct and positive in its operation despite variations in its particular orientation or mounting.

Other objects together with the foregoing are attained in the form of the invention described in the accompanying description and illustrated in the accompanying drawings, in which:

FIGURE 1 is an elevation from the rear or feeding end of the egg carton setup machine pursuant to the invention;

FIGURE 2 is a side elevation of the egg carton feeding machine;

FIGURE 3 is a plan of the egg carton machine, the

2

plane of the plan being shown in FIGURE 2 by the arrows 3—3;

FIGURE 4 is a detailed partial view, being illustrated in section, the plane of which is taken on the line 4—4 of FIGURE 3;

FIGURE 5 is a cross section similar to FIGURE 4, but showing a portion of the machine in section as indicated by the line 5—5 of FIGURE 1;

FIGURE 6 is a view similar to FIGURES 4 and 5, but showing a portion of the machine in cross section, the plane of which is illustrated by the lines 6—6 of FIGURE 1;

FIGURE 7 is a view like FIGURES 4, 5 and 6, being a cross section, the plane of which is indicated by the line 7—7 of FIGURE 1;

FIGURE 8 is an enlarged detail showing in plan a part of the conveyor mechanism for advancing the erected cartons;

FIGURE 9 is a plan of the obverse face of a carton blank as it is initially fed into the machine;

FIGURE 10 is a view similar to FIGURE 9, but is a plan of the reverse face of the carton blank of FIGURE 9;

FIGURE 11 is a perspective view of an erected egg carton pursuant to the invention, a portion of the carton being removed to reduce the size of the figure; and

FIGURE 12 is a side elevation of a number of erected egg cartons in the discharge position after the machine is through with them.

While the egg carton erecting machine pursuant to the invention can be embodied in a number of different forms, it has successfully been employed in practice in the form shown herein and particularly for use in connection with cartons of the sort shown in FIGURES 9—12 inclusive.

Cartons of this sort are well known in the trade and are described in detail in the above-identified patent. They comprise a generally rectangular sheet 6 of paper stock or fiberboard material folded along a fold line 7 to provide a lower panel 8 having a leading portion 9 and a trailing portion 11. Disposed over the leading portion

40 of the lower panel is an upper panel 12 at its trailing edge 13 secured by glue or comparable adhesive to the lower panel. The leading portion of the carton blank has a double thickness and the trailing portion has but a single thickness. There are numerous score lines 16 and cut lines 17. These are provided particularly for the interengagement of various portions of the carton. The forward portion of the lower panel is also provided with a number of apertures such as 18 and 19 having particular functions in the blank and in the erected carton.

In the present instance the carton blank is generally symmetrical on either side of an interrupted cut line 20 so that when it has been erected and loaded the carton can readily be separated into two equivalent half packages. 45 The carton blank generally is of a standard size, but may vary slightly in dimension due to changes in humidity and other atmospheric effects. The carton blank may change in detail construction from time to time depending on other considerations, but generally is handled in quantity 50 in the machine of the present invention. When erected the carton has a number of partitions 21 and 22 turned on hinge lines 23 and 24 to assume a generally upright position. Thrust upwardly between the partitions are folded portions 26 of the lower panel 8, these upstanding portions 26 forming an inverted V and having projections 27 interengaging in openings 28 in the partitions to provide interlocks.

The machine comprises a frame 31 made up of various structural members extending approximately to waist height. These form and include a generally planar table 32 extending from one end of the machine to the other with certain openings and interruptions therein. The table, as 55

70

especially shown in FIGURE 3, is approximately rectangular and is inclined downwardly in the direction of advance of the cartons, although this is not essential and the table can be either horizontal or inclined in the other direction, depending upon the requirements of a particular installation.

Adjacent one end of the frame 31 and overlying the table is a yoke 33 to which are attached upright bars 34 serving as positioning stops for a pile or stack of carton blanks of the sort described. These carton blanks are positioned over a roller 35 against the bars 34 and are partly positioned by upstanding stops 36 so that they are located in order. The cartons are all arranged with the lower panels downwardly and with the upper panels overlying the forward portion thereof on the upper side, appearing as illustrated in FIGURE 9 when seen from above. The bars 34 are adjustable lengthwise and are slightly spaced from the table 32 to leave a passageway 37 of sufficient height to accommodate but a single one of the double thickness carton blanks at any one time. The height of the passageway 37 is adjustable.

Acting periodically during the operation of the machine is a means for individually withdrawing the lowermost one of the carton blanks from the stack. This means includes a group of radial feeding fingers 38, each extending from a rotary shaft 39 mounted in journals 41 on the frame 31. A sprocket 42 on the shaft 39 is driven by a chain 43 from a cross shaft 44 also mounted on the frame 31. An intermediate sprocket 46 is also secured on the shaft 44 and is connected by an intermediate chain 47 to a sprocket 48 on a chain shaft 49 journaled on the frame 31. A drive belt 51 is in engagement with a driven pulley 52 and a drive pulley 53, the former being secured to the shaft 49 and the latter being arranged on a shaft 54 mounted on the frame. Another belt 56 extends from a pulley 57 on the shaft 54 to a drive pulley 58 on a variable speed drive 59 joined to a motor 61. The variable speed drive 59 affords some adjustment in the capacity or output rate of the machine and is effective to drive through the various belts and chains, so that the feeding fingers 38 make one revolution at an appropriate time.

When the shaft 39 revolves, the fingers 38 periodically appear through openings 64 in the table 32 and rise above the table and move in an advancing direction just enough to interengage with the edges of the apertures 18 in the lower panel 8. After abutting the edges of such openings, the fingers 38 during the final portion of their advancing and lowering movement strip the lowermost carton blank from the stack and advance it through the opening 37 or passageway 37 and then descend out of engagement. This advancing movement is not great but is sufficient to withdraw or start the withdrawal of the lower blank from the stack.

As it is so advanced and withdrawn, the lower blank is brought with its leading double edge into immediate juxtaposition with a pair of feeding rolls or drive rollers 66 and 67. The uppermost of these rollers is just above the table 32, whereas the top of the lowermost of the rollers is substantially tangent to the surface of the table. The two rollers are of yieldable material and are normally in fairly light contact, so that they rotate in unison in a feeding direction. Rotation of the lower roller occurs since the lower roller 67 is provided with a sprocket 68 connected by a chain 69 to a sprocket 71 on the shaft 49. As the lowermost detached carton blank is advanced through the passageway 37 by the fingers 38, it passes over an idler roll 72 (FIGURE 4) and engages between the drive rollers 66 and 67. Thereupon the rollers 66 and 67 continue the withdrawal of the lowermost carton blank from the stack and advance the withdrawn carton blank entirely through the aperture 37.

The table on the discharge side of the feed rollers is spanned by an arch 73 mounted on the frame. Depending from the arch is a brake plate 74 secured in such

a fashion as to provide a converging throat 76. The plate 74 is conveniently of a somewhat springy material and is so closely approached to the upper surface of the table 32 as to provide a restricted passage 77 in conjunction therewith.

As the detached carton blank begins to emerge from the drive rollers 66 and 67, it is fed into the converging throat 76 and introduced into the restricted passage 77. The rollers are effective to advance the carton blank against the restraining friction of the brake plate 74 until such time as the advancing blank disengages from the rollers. The particular position at which the blank stops on the table 32 is not precisely fixed, but occurs within a reasonable area or zone, depending upon the velocity of rotation of the feed rollers, the particular amount of friction imposed by the brake plate 74 and other factors, such as the coefficient of friction of the material of the carton. Even though the precise stopping place of the carton blank is not fixed, the blank does stop within an area or zone appropriate for further handling.

In the stop zone, as shown in FIGURE 5, the theretofore flat carton is subjected to a partial lifting operation. On a cross shaft 81 suitably supported on the frame 31 is a plurality of opening fingers 82 having rather sharply curved pointed projections 83. The shaft 81 is connected to a link 84 by a lever 86 and a pivot pin 87. The link 84 is itself connected by a pivot pin 88 to a rocker lever 89 having a journal 91 mounted to rotate on a shaft 92 on the frame 31. The rocker lever 89 carries a cam follower 93 situated in a cam groove 94 formed in a cam 96 secured to the shaft 44. Thus, as the shaft 44 rotates the cam follower 93 causes a corresponding oscillation of the shaft 81 and the movement of the opening fingers 82 between a retracted position shown by the dotted lines in FIGURE 5 and the full line position shown therein.

The lifting fingers move from their retracted position through an appropriate gap in the table 32 and travel upwardly through the openings 18 in the forward part of the leading portion 9 of the lower panel 8. The opening fingers 82 in rising above the level of the lower panel encounter the superposed upper panel 12 which has no openings therein in this area. Thus the rising opening fingers 82 lift the upper panel and separate it from the lower panel substantially as shown in FIGURE 5. The opening fingers come substantially to a fixed or set final uppermost position as established by the shape of the cam groove 94, and hence serve as precise stops or locators for the positioning of the carton blank. At this stage, therefore, the carton blank is appropriately positioned and aligned and the upper panel is lifted slightly from the lower panel.

In this position, the carton blank underlies a fixed erecting head 101 (FIGURE 6) which bridges the table 32 as it extends from one side to the other of the frame 31. The erecting head 101 has certain upright faces 102 and 103. These are referred to as "upright" since they extend substantially at right angles to the general plane of the table 32, despite the fact that they may or may not be inclined to the vertical.

While the carton blank is partly opened and held by the opening fingers 82, a number of erecting fingers 106 become effective. These are all mounted on a cross bar 107 secured to a lever mechanism 108 mounted on a cross shaft 109 secured to the frame 31. The lever mechanism 108 is moved from the broken line position shown in FIGURE 6 into the full line position therein by means of a link 111 connected by a pivot 112 to the lever mechanism 108 and also connected by a pivot 113 to a rocker lever 114. A journal 116 is secured to the rocker lever 114 and is mounted on the cross shaft 92. The outboard end of the rocker lever 114 carries a cam follower 117 operating in a groove 118 in a cam 119 secured to the shaft 44. As the shaft 44 revolves, the cam 119 likewise revolves and causes an oscillation of the rocker lever 114

and a similar motion of the link 111. This produces the desired operation of the erecting fingers 106.

As the erecting fingers 106 move from their retracted position below the table 32, they rise through the openings 18 in the forward portion of the lower panel and, finding no corresponding openings in the upper panel, abut against that panel and lift it into a generally erect position. The ends of the erecting fingers are so disposed and their stroke is such that the finger tips end exactly at a fold line in the carton between the forward panel and the top panel thereof with the top panel in close abutment with the upright faces 102 and 103 of the erecting head 101. The operation of the erecting fingers 106 in lifting the upper panel is greatly facilitated by the fact that the opening fingers 82 have initially spread the upper panel away from the lower panel and have initiated some of the hinge movement on the fold lines which is later augmented by the erecting fingers 106. Furthermore, since there is an upward force on the carton blank as the erecting fingers 106 are operating, the hooked portion of the opening fingers 82 in overlying the now forward portion of the lower panel holds that panel substantially in contact with the plane of the table 32 and prevents undue rising movement of the leading portion of the lower panel.

Next in the sequence of operations is the folding of the partitions 21 and 22 from their initial location substantially coplanar with the remainder of the carton blank into an upright position or a position at right angles to the carton blank. Arranged to move from a retracted position behind the erecting head 101 and a forward position is a turning plunger 131 having a pair of cross bars 132 and 133 from which extend a plurality of turning dies 134. The plunger 131 at its lower end remote from the table 32 is mounted on a cross shaft 136 mounted on the frame 31. Also secured to the cross shaft 136 is a lever 137 carrying a cam follower 138 designed to run in the groove 139 of a cam 141 on the shaft 44. As the shaft revolves, the follower 138 causes oscillation of the plunger 131 and causes the turning cams 134 to move from their retracted position as shown in the broken lines in FIGURE 6 and behind the erecting head to a forward position as shown by full lines in FIGURE 6. As the turning plunger moves forwardly, the cams 134 interengage with the projecting portions of the partitions 21 and 22 and turn them about the hinge lines 23 and 24 and hold the partitions in a position substantially at right angles to the top and bottom of the carton blank.

While the turning plunger is still in its forward location, means are effective to fold and erect the bottom of the carton. As particularly shown in FIGURE 7, a folding plate 151 extending transversely across the table 32 is appropriately moved from the dotted line position shown in FIGURE 7 into the full line position shown therein. The folding plate 151 is mounted on a pair of levers 152 carried by a shaft 153 on the frame 31. Also mounted on the shaft 153 is a lever 154 connected by a link 156 to a rocker 157 carried by a journal block 158 on a shaft 92. On the rocker 157 is a follower 161 operating in a cam groove 162 cut in a cam 163 mounted on the shaft 44. Thus as the shaft 44 rotates, the rocker 157 serves appropriately to move the folding plate 151. At an appropriate time when the partitions are held in their finally erected position by the cams 134, the plate 151 comes into position and in doing so engages the bottom of the carton blank and puts a central fold in it to leave an upstanding transverse ridge and to interlock the fingers 27 with the openings 28 in the partitions and to hold the ridge and the partitions in interlocked condition.

When the folding plate has been withdrawn to its posi-

tion below the table 32, a pair of side conveyors is effective. The conveyors include a pair of side chains 165 and 167 trained around appropriate sprockets on shafts 168 and 169 journaled on the frame 31. The shaft 169 is connected by a chain 171 to be driven by the shaft 49 in unison with the remainder of the structure. At appropriate intervals, the chains 165 and 167 and at points opposite each other carry mounting plates 172 (FIGURE 8). To each of the mounting plates a lever 173 is joined by a pivot connection 174. A spring 176 is connected at one end to a pin 177 on the plate 172 and is connected at the opposite end to a pin 178 to the lever, so that the lever normally is moved into a retracted position as shown by the broken lines in FIGURE 8.

As the chains 165 and 167 advance, the levers 173 approach cam rails 179 mounted on the frame 31. Rollers 181 on the levers 173 abut the cam rails and roll therealong so as to pivot the levers 173 from the broken line position into the full line position as shown in FIGURE 8. As the levers pivot in this fashion, they move engaging fingers 182 into position to encounter the projecting portions of the already erected carton from which the turning dies and the folding plate 151 have just been withdrawn. The conveyor then carries this erected carton in the direction of the arrow 183 in FIGURE 8 to a storage platform 184 at the discharge end of the machine and in effect constituting the terminal part of the table 32. The erected cartons can then be discharged from the plate 184 in any desired fashion or can be temporarily accumulated thereon. The discharging cartons automatically nest as shown in FIGURE 12.

What is claimed is:

An egg carton setup machine comprising:

a frame,

means for supporting a stack of carton blanks on said frame,

each of said carton blanks having a lower panel with apertures in the leading portion thereof,

means for feeding said carton blanks one at a time from said stack to an erecting zone on said frame,

means for engaging a carton blank to position it at said erecting zone,

means on said frame and operating through said apertures for erecting an opened carton blank,

a pair of conveyor means on said frame movable along parallel paths on opposite sides of a carton blank from a position displaced from said erecting zone to and past said erecting zone to a delivery area,

a pair of pusher fingers each pivotally mounted about an upright axis on one of said conveyor means,

a cam means along and outward of said parallel paths extending from said erecting zone to said delivery zone and engageable by said fingers to extend said fingers inward from said paths as they pass an erected carton at said erecting zone to enter said erected carton and engage the edges of a leading upright panel thereof, and

means normally biasing said fingers into retracted positions,

said cam means releasing said fingers at said delivery area.
